zeug-und-Motorenwerke, A. G., Dessau, Ger-
many, a corporation of Germany

Application August 6, 1940, Serial No. 351,600
In Germany June 30, 1939

8 Claims. (Cl. 103—41)

This invention is directed to fuel injection pumps for internal combustion engines, and is particularly directed to the lubrication of such pumps.

Fuel injection pumps of the type under consideration, consist of a pumping piston closely fitting within a cylinder. Fuel is supplied to the pumping chamber of the cylinder and is forced outwardly therefrom to the engine. Lubricating oil is applied directly to the piston at a point remote from the pumping chamber. Special difficulties are created in the lubrication of the pump for the following reasons.

It is necessary that the oil supply pressure be kept slightly greater than the fuel supply pressure to the pumping chamber so that the fuel, such as gasoline and which has no lubricating properties, will not dilute or replace the oil film between the piston and the cylinder walls. Too great an oil supply pressure would mean that an excessive quantity of oil, that is more oil than is needed to lubricate the piston, would flow past the piston into the pumping chamber, and there would be mixed with the fuel and wasted. The difficulty of ascertaining a correct oil feed pressure is complicated because of the increase in fuel pressure in the pumping chamber during the piston pumping stroke, this increase in fuel pressure being greater than the oil supply pressure so that fuel is forced between the cylinder and piston walls, with the result that the lubricant is diluted or displaced.

In the prior art attempts have been made to achieve the proper lubrication of the pump and a substantially constant oil supply pressure with slow seepage of oil past the piston by providing an annular oil supply groove for the piston, and an annular oil collection and sealing groove between the oil supply groove and the pumping chamber, this second groove being so far removed from the pumping chamber that it remains constantly covered and sealed regardless of the position of the piston in the cylinder. This arrangement has not been entirely successful inasmuch as the reciprocation of the piston builds up pressure in the second groove, which pressure in time increases to such a degree as to interfere with the proper operation of the pump. This pressure is created by the second groove becoming filled with fuel forced down between the piston and cylinder wall during the pumping stroke of the piston, that is during the period when the highest pressure prevails in the pumping chamber. This fuel is unable to flow back to the pumping chamber during the suction stroke of the piston as the pressure in the second groove is not great enough to cause a liquid flow between the piston and cylinder. However, the pressure in the second groove becomes greater

than the oil feed pressure so that lubrication of the piston ceases.

An attempt to overcome this difficulty has been made by connecting the second groove with the fuel inlet line to the pump by means of a bore. By so doing, the oil and fuel pressure in the second annular groove is never higher than the intake pressure to the fuel pump which, of course, is less than the oil feed pressure to the pump.

Difficulties, however, have been experienced with this construction because the bore, which is obliquely disposed in the pump, creates a complicated and expensive piece of construction. Particularly this construction has been unsuccessful in the manufacturing of the cylinder blocks inasmuch as during the hardening of the blocks, the oblique bore very often cracks open at its angular top, and the number of spoiled and rejected cylinder blocks has been extraordinarily high.

It is an object of the instant invention to produce a fuel pump in which, by means of a very simple construction entirely within the cylinder, a substantially constant pressure differential is maintained between the oil feed pressure and the oil seal pressure.

Another object of the invention is to construct an oil injection pump, the cylinder block of which can be readily machined and heat treated without cracking, while at the same time an adequate lubricating system for the pump is obtained.

Another object of the invention is to construct a fuel injection pump having a novel oil sealing means by reason of which a mixture of oil and fuel is kept at a minimum, while excess pressures which would interfere with the operation of the pump are avoided.

Another object of the invention is to construct a fuel injection pump in which the oil pressure in the oil sealing groove is kept appreciably below the oil inlet pressure during the entire working range of the pump.

Generally these objects are accomplished by providing the cylinder or the piston with two annular grooves, one of which is spaced from the pumping chamber and constitutes the oil supply, while the other groove is located so that communication is established between it and the pumping chamber for a short time during a portion of the piston stroke. This communication may be established by forming the oil seal groove in the cylinder wall and having it communicate with the pumping chamber of the cylinder through a recess in the piston when the piston is adjacent its outer dead center position, or by leaving at the piston outer dead center position such a small sealing surface between the piston and cylinder walls that communication is effectively, if indirectly, established between the groove and the pumping chamber. In a multi-cylinder pump, further release of pressure from

the oil seal grooves can be accomplished by inter-connecting the oil seal grooves of the various cylinders with each other so that when the pressure is produced in the groove during the pumping stroke in one cylinder, it is released by the suction stroke taking place in a second cylinder. If desired the grooves can be formed in the piston instead of in the cylinder wall.

The means by which these objects may be accomplished are shown more clearly in the accompanying drawings in which:

Fig. 1 is a cross sectional view of a portion of a fuel injection pump showing the lubricating construction of this invention, with the piston positioned at its outer dead center position in the cylinder.

Fig. 2 is a similar view, but showing the piston shortly after starting its pumping stroke, and at the instant the oil seal groove is covered by the piston.

Fig. 3 is a similar view, but showing the piston at the position where the fuel inlet port is closed.

Fig. 4 is another similar view, showing the piston at its inner dead center position.

Fig. 5 is a cross sectional view on the line 5—5 of Fig. 1.

Fig. 6 is a view similar to Fig. 1, but showing a modified form of the invention in which the oil seal groove is not uncovered when the piston is at its outer dead center position.

Fig. 7 is a view similar to Fig. 1, but showing a modified form of the invention as applied to a multi-cylinder pump, and

Fig. 8 is a cross sectional view on the line 8—8 of Fig. 7.

In Fig. 1 the cylinder block 2 is fitted with a cylinder lining 4 within which a piston 6 reciprocates. Fuel passes through the fuel inlet 8, through a port 10 in cylinder lining 4, into the pumping chamber 12 of the pump. This construction is typical of fuel injection pumps, the pumped fuel passing from chamber 12 through a check valve, not shown, to the combustion chamber of the engine.

To lubricate piston 6, oil is supplied through bore 14 in block 2, through port 16 in cylinder lining 4, to an annular groove 18 formed in the inner surface of cylinder lining 4. It is obvious that oil supplied through bore 14 will lubricate the surfaces of the piston and cylinder lining. To insure constant lubrication, the oil pressure supplied through bore 18 is greater than the pressure of the fuel supplied through bore 8.

An oil seal between the groove 18 and the pumping chamber 12 is provided by a second annular groove 20 in the cylinder wall adjacent pumping chamber 12. Piston 6 has a recess 22 extending from its upper surface to a so-called unloading channel 24. Groove 20 is so positioned with respect to unloading channel 24 that when the piston is at its outer dead center position as shown in Fig. 1, groove 20 is uncovered to establish communication from groove 20 through channel 24 and recess 22, into pumping chamber 12. As the piston starts on its pumping stroke, Fig. 2, this communication is cut off just before the top surface of the piston closes off fuel port 10. When the fuel inlet port 10 is closed, groove 20 is cut off as shown in Fig. 3 by the piston length between the groove and the edge of channel 24, while when the piston has reached its inner dead center position at the completion of this pumping stroke as shown in

Fig. 4, a substantial sealing surface exists between the channel 24 and groove 20.

At the beginning of the pumping stroke of the piston, that is when the piston is at its outer dead center position, the oil supplied through bore 14 has a greater pressure than the fuel supplied through bore 10 into pumping chamber 12, and therefore oil will tend to seep along the surface of the piston from groove 18 toward groove 20 to lubricate the piston. As the pumping stroke takes place, oil is carried by the piston wall toward groove 20, while at the same time the pressure increase on the fuel in pumping chamber 12 will tend to force fuel toward groove 20. However, as the pumping stroke increases, the distance from channel 24 to groove 20 also increases, and consequently the oil seal tends to prevent the fuel from reaching groove 20. Hence there is substantially no increase in pressure in the groove 20 due to the increase in pressure in pressure chamber 12 so that oil will flow to groove 20. On the return stroke of the piston, when the outer dead center position is reached, communication is established between groove 20 and the pumping chamber so that any excess pressure built up in groove 20 is immediately released. A building up of pressure in groove 20 by successive reciprocations of the piston is prevented. Consequently the average pressure in groove 20 at any time, lies appreciably below the oil feed pressure, and no excess pressures are built up in groove 20 which would interfere with the proper working of the pump. At the same time, oil in groove 20 serves to lubricate the entire surface of the piston.

In Figs. 1 to 5, a direct communication between the groove 20 and pumping chamber 12 is obtained. The piston can be constructed so that, as shown in Fig. 6, an indirect communication is maintained between the groove and the chamber. For example, the unloading channel 24a in piston 6a is so constructed that the surface of the piston always covers groove 20a, but a very little distance is left between groove 20a and channel 24a. Consequently the fuel under excess pressure in groove 20a can escape between the cylinder wall and the piston into channel 24a when the piston is at its outer dead center position.

The invention can also be used with particular advantage in a multi-piston pump as shown in Figs. 7 and 8. In this pump the cylinder block 30 is provided with a plurality of cylinders in line, with pistons 32 to 37, respectively, therein. Each piston is constructed as the piston shown in Figs. 1 to 5, inclusive, and each cylinder has a pumping chamber 44 from which fuel is passed through check valve 46 to the combustion chamber of an engine. Fuel is supplied to the pump through a bore 48 common to all the cylinders, each of which is connected to bore 48 by its individual port. Oil is supplied to the pistons and cylinders through a bore 50 common to all the cylinders, through ports for each of the cylinders, respectively, to annular groove 52 in each cylinder wall around each piston. An oil seal groove 54 is formed in each cylinder wall and associated with a so-called unloading channel 56 which communicates through a recess 58 in the piston head for establishing communication between groove 54 and pumping chamber 44 when the piston is at its outer dead center position. In this multi-cylinder pump, all of the grooves 54 are inter-connected by a bore 60. Consequently when one piston is at its inner dead

center position during its pumping stroke, at least one other of the pistons will be at its outer dead center position in its suction stroke, and will relieve the excess pressure in each of the grooves 54 through the common bore 60. Therefore there is no chance of any substantial pressure being built up in any of the grooves 54 as there is always a relief of pressure in the grooves through bore 60. This construction has the further advantage in that the cylinder block is simply and inexpensively formed. A positive lubrication of each piston without undue waste of oil is obtained as in the construction of Figs. 1 to 5.

It is thus apparent that in the construction of fuel injection pumps which require a high degree of accuracy in manufacture, an oil sealing device has been created which is manufacturable without the risk of waste, while at the same time a positive flow of lubrication fluid is insured from the fuel supply groove to the oil seal groove without the danger of having an undue loss of oil by leakage into the pumping chamber, or without having a failure of the pump occasioned by a deficiency in lubricant by reason of the fuel diluting or replacing the lubricant. Extended tests have demonstrated the fact that the pressure in the oil seal groove remains at a substantially constant value below the oil supply pressure.

Having now described the means by which the objects of the invention are obtained, we claim:

1. In a fuel injection pump for an internal combustion engine, said pump having a piston slideable in a cylinder and defining a pumping chamber therein, and means for supplying fuel under a first pressure to said chamber lubricating means for said pump comprising an oil supply inlet into said cylinder remote from said chamber, means for supplying oil to said inlet under a second pressure greater than said first pressure, an oil sealing groove in said cylinder between said inlet and said chamber, and means for establishing communication between said groove and said chamber within said cylinder to reduce the pressure in said groove to a pressure intermediate said first and second pressures when said piston is at its outer dead center position.

2. In a fuel injection pump as in claim 1, said means for establishing communication comprising a channel in said piston.

3. In a fuel injection pump for an internal combustion engine, said pump having a piston slideable in a cylinder and defining a pumping chamber therein, and means for supplying fuel under a first pressure to said chamber; lubricating means for said pump comprising an annular oil supply groove in the wall of said cylinder remote from said chamber, means for supplying oil to said oil supply groove under a second pressure greater than said first pressure; an annular oil sealing groove in said cylinder wall between said oil supply groove and said chamber, and means for establishing communication between said sealing groove and said chamber, within said cylinder, to reduce the pressure in said sealing groove to a pressure intermediate said first and second pressures during the movement of said piston adjacent its outer dead center position.

4. In a fuel injection pump for an internal combustion engine, said pump having a piston the head of which is recessed from its upper surface to a peripherally extending unloading channel, a cylinder in which said piston slides and defines a pumping chamber, and means for supplying fuel under a first pressure to said chamber; lubricating means for said pump comprising an annular oil supply groove in the wall of said cylinder remote from said chamber, means for supplying oil to said oil supply groove under a second pressure greater than said first pressure; an annular oil sealing groove in said cylinder wall between said oil supply groove and said chamber, and means for establishing communication between said sealing groove and said chamber, within said cylinder, to reduce the pressure in said sealing groove to a pressure intermediate said first and second pressures during the movement of said piston adjacent its outer dead center position.

5. In a fuel injection pump for an internal combustion engine, said pump having a piston the head of which is recessed from its upper surface to a peripherally extending unloading channel, a cylinder in which said piston slides and defines a pumping chamber, and means for supplying fuel under a first pressure to said chamber; lubricating means for said pump comprising an annular oil supply groove in the wall of said cylinder remote from said chamber, means for supplying oil to said oil supply groove under a second pressure greater than said first pressure; an annular oil sealing groove in said cylinder wall between said oil supply groove and said chamber, and means for establishing communication between said sealing groove and said chamber, within said cylinder, to reduce the pressure in said sealing groove to a pressure intermediate said first and second pressures.

15 6. In a fuel injection pump for an internal combustion engine, said pump having a piston the head of which is recessed from its upper surface to a peripherally extending unloading channel, a cylinder in which said piston slides and defines a pumping chamber, and means for supplying fuel under a first pressure to said chamber; lubricating means for said pump comprising an annular oil supply groove in the wall of said cylinder remote from said chamber, means for supplying oil to said oil supply groove under a second pressure greater than said first pressure; an annular oil sealing groove in said cylinder wall between said oil supply groove and said chamber, and means for establishing communication between said sealing groove and said chamber, within said cylinder, to reduce the pressure in said sealing groove to a pressure intermediate said first and second pressures.

20 7. In a fuel injection pump for an internal combustion engine, each cylinder having a piston slideable therein and defining a pumping chamber, lubricating means for said pump comprising oil supply means for each cylinder remote from said chamber, oil sealing means for each cylinder between said oil supply means and said chamber, and means for providing constant direct communication between all of said oil sealing means.

25 8. In a fuel injection pump for an internal combustion engine, each cylinder having a piston slideable therein and defining a pumping chamber, lubricating means for said pump comprising oil supply means for each cylinder remote from said chamber, an oil sealing groove for each cylinder positioned between said supply means and said chamber, and a channel common to all of said grooves and providing communication therebetween.

30 9. In a fuel injection pump comprising two elements consisting of a cylinder and a piston slideable therein, and defining a pumping chamber, means for supplying fuel at a first pressure to said chamber, lubricating means for said pump comprising a lubricant supply inlet into said cylinder remote from said chamber, means to supply a lubricant to said inlet at a second pressure greater than said first pressure, said elements having two grooves therearound, one of said grooves being adapted to communicate with said inlet, and means for establishing communication between the other groove and said chamber when said piston is adjacent its outer dead point, the surfaces of the elements opposite said grooves fitting tightly with respect to each other at all times when said piston is away from its outer dead point.
